UNITED STATES PATENT OFFICE

ROBERT CAMPBELL, OF WOOSTER, OHIO.

IMPROVEMENT IN WASHING-MACHINES.

Specification forming part of Letters Patent No. **222,623**, dated December 16, 1879; application filed December 26, 1878.

To all whom it may concern:

Be it known that I, ROBERT CAMPBELL, of the city of Wooster, in the county of Wayne and State of Ohio, have invented a new and useful Improvement in Washing-Machines, of which the following is a specification.

Washing-machine's operating upon this principle have been before constructed.

My invention relates to certain improvements in their construction; and it consists in the combination of a catch-lid hinged upon a movable cover which supports the axis of the operating-lever, both adjusted so as to enable the catch-lid to connect and fasten upon a pivoted wash-board (which I do not claim as part of my invention) in such a way as to form a corrugated perpendicular surface to resist the pressure of the dasher of the machine while in operation, whereby the clothes in the machine-box are made to revolve at each stroke of the dasher, and at the same time the wash-box is tightly closed to prevent the escape of water and steam.

The object of my invention is to provide a more simple and perfect method of opening and closing the wash-box than heretofore, and to utilize the corrugated surface of the wash-board by making the lid of the box clasp and hold the same in a perpendicular position to resist the force of the dasher.

In the accompanying drawings, in which similar letters of reference indicate like parts, Figure 1 is an interior view of the device embodying my invention. Fig. 2 is a detail view of the combination of dasher and movable cover, with the catch-lid hinged upon the same.

In Fig. 1, L and W indicate the respective

positions of the catch-lid and adjustable wash-board when joined to close up the wash-box B. L' and W' indicate respective positions of the same when the wash-box is open.

The wash-board W is pivoted at each end of its base into the sides of the wash-box at P and P'. The catch-lid L is hinged upon the movable cover C at i and i', and the wash-board and lid, when closed upon each other, are secured in position by means of a catch, O, upon the lid L.

The movable cover C is constructed with a box, T, at each end, in which the pivots D and D' of the dasher operate, and these boxes rest in cavities at each side of the wash-box, and the cover C is fastened securely in position to operate the dasher by means of buttons K and K'.

The adjustable handle H moves in the slotted lever-shaft E upon a pivot, A, in the top of the shaft, and is adjusted to any desired elevation by means of a pin, s, passing through the lever-shaft and a corresponding hole, s', in the arc of the handle.

What I claim is—

The box B and the removable cover C, having bearings T for the journals of the beater, and the lid L, hinged to the cover and provided with the catch O, in combination with the beater and the pivoted wash-board, substantially as described, and for the purposes set forth.

ROBERT CAMPBELL.
